(57) **CLAIM**

The ornamental design for a shelving system, as shown and described.

DESCRIPTION

FIG. 1 is a top, rear, left-side perspective view of a shelving system embodying our design;

FIG. 2 is a close-up view of a portion thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a bottom plan view thereof;

FIG. 8 is a close-up view of FIG. 7;

FIG. 9 is a top plan view of the shelving system of FIG. 1; and, FIG. 10 is a close-up view of FIG. 9.

All features in phantom line form no part of the claimed subject matter. Due to limitations in the ability to illustrate certain features in phantom line in the overall views of FIGS. 1 and 7, certain unclaimed features of the shelving system are shown only in the close-up views of FIGS. 2 and 8.
